G. M. EATON.
LOCOMOTIVE.
APPLICATION FILED DEC. 14, 1916.

1,274,398.

Patented Aug. 6, 1918.

UNITED STATES PATENT OFFICE.

GEORGE M. EATON, OF PITTSBURGH, PENNSYLVANIA, ASSIGNOR TO WESTINGHOUSE ELECTRIC & MANUFACTURING COMPANY, A CORPORATION OF PENNSYLVANIA.

LOCOMOTIVE.

1,274,398

Specification of Letters Patent. Patented Aug. 6, 1918.

Application filed December 14, 1916. Serial No. 136,874.

To all whom it may concern: Be it known that I, George M. Eaton, a citizen of the United States, and a resident of Pittsburgh, in the county of Allegheny and State of Pennsylvania, have invented a new and useful Improvement in Locomotives, of which the following is a specification.

My invention relates to electric locomotives and particularly to the driving connections between the propelling motors and the driving wheels.

One object of my invention is to provide a locomotive with a jack shaft and a side rod connection between the propelling motors and the driving wheels which shall be light and rigid in construction and substantially free from lateral vibration or from extreme whipping stresses and shall insure smooth running characteristics at high speeds.

Another object of my invention is to provide a locomotive of the above-indicated character that shall have the motor and the side rods located so that the center lines thereof radiate from one point which rotates about a substantially fixed center.

Another object of my invention is to provide a locomotive of the above-indicated character having two motor and two side rods which radiate from one central point and two of the rods directly and pivotally connected to two other of said rods.

Another object of my invention is to provide a locomotive which shall be provided with a jack shaft to restrain the motor and the side rods from lateral vibration and permit the rods to have a limited free movement relative thereto in the plane of the rod system.

A further object of my invention is to provide a locomotive of the above-indicated character that shall have all the motor and the side rods thereof disposed in the same vertical plane, whereby the pins connecting the rods together and to the various cranks are relieved of excessive stresses.

More specifically, my invention embodies a locomotive provided with two articulated running gears, each of which comprises a plurality of pairs of driving wheels, two auxiliary trucks and two motors mounted above the driving wheels. The motors are joined to the driving wheels by means of side and motor rods which are preferably

connected to a jack shaft disposed between two pairs of the driving wheels.

In the accompanying drawing illustrating my invention, Fig. 1 is an elevational view of a portion of a locomotive constructed in accordance with my invention; Figs. 2 and 3 are sectional views of the jack shaft illustrated in Fig. 1; Figs. 4 and 5 are side-elevational and plan views, respectively, of portions of a modification of my invention in which the motor rods are directly connected to each other and to oppositely disposed side rods; Figs. 6 and 7 are side-elevational and plan views, respectively, of portions of a modification in which the motor rods are directly joined to each other and to oppositely disposed side rods; Figs. 8 and 9 are side-elevational and plan views, respectively, of portions of a modification in which the side rods are directly joined to each other and to adjacently disposed motor rods; Figs. 10 and 11 are side-elevational and plan views, respectively, of portions of a modification in which the side rods are directly connected together and to the oppositely disposed motor rods; and Figs. 12 and 13 are side-elevational and plan views, respectively, of portions of a modification in which one motor rod is directly connected to the two side rods and one side rod is directly connected to the two motor rods.

Referring to Fig. 1 of the drawing, a locomotive 1 embodies a cab 2 and two articulated running gears 3 and 4 which are connected together by an articulated connection 5 and to the cab 2 by pivotal connections 6, one only of which is illustrated. Each of the running gears comprises a four-wheel pivotal outer truck 7, a two-wheel radial inner truck 8 and three pairs of driving wheels 9, 10 and 11. The driving wheels 9, 10 and 11 are respectively provided with axles 12, 13 and 14 which have driving cranks 15, 16 and 17 mounted thereon.

A jack shaft 18, having cranks 19 mounted thereon, is disposed between the two pairs of driving wheels 9 and 10 and two motors 20 and 21, having cranks 22 and 23 mounted on the armature shafts thereof, are located substantially above the pairs of driving wheels.

As locomotives in common use are supplied with similar driving rods on the two sides thereof, the rods on one side only are described and referred to in detail. The

cranks 22 and 23 of the motors 20 and 21 are respectively pinned to two motor rods 24 and 25. Each of the cranks 15 of the pair of driving wheels 9 is pinned to a side rod 26, and the cranks 16 and 17 of the driving wheels 10 and 11 are pinned to a side rod 27. The rod 25 is provided with a bifurcated end portion which fits over an end portion of the motor rod 24 and is pinned thereto by a jack-shaft pin 28. The bifurcated end portion of the motor rod 25 also fits over the side rod 27 and is pinned thereto by a pin 29. The side rod 26 is provided with a bifurcated end portion which extends over, and is pinned to, an end portion of the motor rod 24.

Referring to Figs. 2 and 3 of the drawing, the motor rods 24 and 25 are directly mounted on a bushing 30 which is loosely fitted to the jack-shaft pin 28 so that the motor and side rods may have a limited free movement, relative to the jack shaft, in the plane of the rod system. However, the jack shaft 28 is provided with a washer 31 and a nut 32 for preventing any lateral vibration of the rods 24 and 25.

In describing Figs. 4 to 13, inclusive, the various elements are designated by reference characters corresponding to those used in Figs. 1 to 3, inclusive. In the modification illustrated in Figs. 4 and 5, the motor rod 25 is provided with a bifurcated end portion which includes end portions of the motor rod 24 and the side rod 26 between arms thereof and is respectively pinned thereto by the jack-shaft pin 28 and a pin 33. The side rod 27 is provided with a bifurcated end portion which includes an end portion of the motor rod 24 between the arms thereof and is joined thereto by means of the pin 29.

In the modification illustrated in Figs. 6 and 7, the motor rod 25 is provided with a bifurcated end portion which includes end portions of the rods 24 and 27 between the arms thereof and is respectively pinned to said rods by pins 34 and 29. The side rod 26 is provided with a bifurcated end portion which includes an end portion of the motor 24 between the arms thereof and is pinned thereto by a pin 33. The motor rod 24 is directly joined to the crank 19 by means of the crank pin 28. In the modification illustrated in Figs. 8 and 9, the side rod 26 is provided with a bifurcated end portion which includes end portions of the motor rod 24 and the side rod 27 between the arms thereof and is pinned to the side rod 27 by the jack-shaft pin 28 and to the motor rod 24 by the pin 33. The motor rod 25 is provided with a bifurcated end portion which includes an end portion of the side rod 27 between the arms thereof and is joined thereto by the pin 29.

In the modification illustrated in Figs. 10 and 11, the side rod 26 is provided with

a bifurcated end portion which is connected to end portions of the motor rod 25 and the side rod 27, and the motor rod 24 is provided with a bifurcated end portion which is pinned to an end portion of the side rod 27. In this modification, the jack-shaft pin 28 serves as a means for connecting the side rods 26 and 27. In Figs. 12 and 13 of the drawing, the motor rod 25 is provided with a bifurcated end portion which is joined to end portions of the two side rods 26 and 27, and the motor rod 24 is provided with a bifurcated end portion which is pinned to the side rod 26. The jack-shaft pin 28 connects the motor rod 25 and the side rod 26 together and to the jack-shaft crank 19.

Although I have shown and described locomotive driving mechanisms embodying more or less specific structural details and arrangement and location of parts, my invention, in its broadest aspect, is not limited in these respects, and many modifications thereof may be effected without departing from the spirit and scope of my invention. I desire, therefore, that only such limitations shall be imposed as are indicated in the appended claims.

I claim as my invention:

1. In a locomotive, the combination with a cab, of two articulated running gears, each of said running gears comprising two auxiliary trucks, a plurality of pairs of driving wheels located between the auxiliary trucks, side-rod members for joining said driving wheels, motors mounted above said driving wheels, and means for joining the motors to a point on the side-rod members intermediate two pairs of said driving wheels.

2. In a locomotive, the combination with a cab, of two articulated running gears, each of said running gears comprising two auxiliary trucks, a plurality of pairs of driving wheels located between the auxiliary trucks, a jack shaft disposed between two pairs of said driving wheels, a plurality of motors mounted above said driving wheels, and rods for joining said jack shaft to the motors and to the driving wheels.

3. In a locomotive, the combination with a cab, of two articulated running gears, each of said running gears comprising a four-wheel pivotal truck, a two-wheel radial truck, three pairs of driving wheels disposed between said radial and said pivotal trucks, a jack shaft disposed between two pairs of the driving wheels, two motors mounted above the driving wheels, and means comprising rod members for joining the jack shaft to the motors and to the driving wheels.

4. In a locomotive, a jack shaft, two motor rods connected to said jack shaft, and two side rods independently and directly joined to said motor rods.

5. In a locomotive, the combination with

5 a plurality of pairs of driving wheels and a plurality of motors mounted adjacent to said driving wheels, of a jack shaft, motor rods for connecting said motors to the jack shaft, and side rods independently and directly joined to said motor rods.

10 6. In a locomotive, the combination with a plurality of pairs of driving wheels and two motors mounted above said wheels, of a jack shaft located between two pairs of said wheels, and four rods for joining said motors to the driving wheels, two of said rods being joined to the jack shaft and the remaining rods being joined to the first-mentioned rods.

15 7. In a locomotive, the combination with three pairs of driving wheels, side rods for connecting said driving wheels, and two motors mounted above said driving wheels, of a jack shaft located between two pairs of said driving wheels, motor rods for joining the motors to the jack shaft, and side rods for joining the driving wheels to the motor rods.

20 25 8. In a locomotive, the combination with a plurality of pairs of driving wheels, two motors mounted above said driving wheels,

and a jack shaft located between two pairs of said driving wheels, of two motor rods and side rods for joining said motors to the 30 driving wheels, and a jack shaft having a pin for joining the two motor rods together, said side rods being pivotally joined to the motor rod adjacent to said jack-shaft pin.

9. In a locomotive, the combination with 35 two motor rods, two side rods and a jack shaft, of a pin mounted on said jack shaft for joining the two motor rods and for preventing lateral vibration of said rods, each of said side rods being pivotally joined to 40 the motor rod adjacent thereto.

10. In a locomotive, the combination with a plurality of motors and a plurality of driving wheels, of two side rods and two motor rods for joining the motors to the 45 driving wheels, said rods being disposed in one vertical plane and each motor rod being directly connected to the other motor rod and also directly and pivotally connected to the adjacent side rod. 50

In testimony whereof, I have hereunto subscribed my name this 24th day of Nov., 1916.

GEORGE M. EATON.
